SELF-PRIMING PUMP

Richard G. Barzen, Kansas City, Mo.

Application December 15, 1936, Serial No. 115,921

1 Claim. (Cl. 103—113)

The present invention relates to self-priming pump constructions, aiming to provide a novel and improved self-priming feature in apparatus of this character.

5 One of the objects of the invention is to provide a construction which is of a simple and automatically adjustable character for cooperation with the pumping means in effecting the priming function.

10 One method of accomplishing this object is to provide a device operating on the injector principle and in cooperation with the pumping means for displacing either gas or liquid from the suction intake or chamber and discharging such gas 15 or liquid into the outlet or discharge line of the pump.

It is also an object of the invention to provide a construction of the character mentioned in which provision is also made for permitting recirculation of liquid from the outlet or discharge line of the pump back to the suction side of the pump for properly supporting the priming operation; and in this connection it is also sought to provide a construction which will be substantially automatic in its operation, as required by varying conditions or needs of the pumping action. One method of accomplishing this result is to provide a nozzle or injector device between the pumping means and discharge line, and of 25 such a character as to exercise a compensating function allowing recirculation of water as required for priming and also automatically restricting or entirely cutting off the discharge connection against the return or recirculation of water after the pump has been fully primed.

It is further sought to provide a substantially valveless construction by so constructing the improved priming feature as to automatically break any siphon action which would otherwise suck 40 away all the priming liquid; another object of this feature of the invention being to render the pump more efficient by preventing leaks on the intake side of the pump from affecting the pumping means.

45 Still another object of the invention is to provide a construction in which the improved priming device will not only accomplish the priming function in a more efficient manner, but may also be adapted to increase the pump's capacity by virtue of the injector action serving to pump liquid in addition to that passing through the pumping device proper.

With the foregoing general objects in view, the invention will now be described by reference to 55 the accompanying drawing illustrating one prac-

tical form of embodiment of the proposed improvements, after which those features and combinations deemed to be novel will be particularly set forth and claimed.

5 In the drawing—
Figure 1 is a vertical sectional view illustrating a self-priming pump constructed in accordance with the present invention, said view representing a section taken on the line 1—1 of Figure 2;

10 Figure 2 is a similar view representing a section taken on the line 2—2 of Figure 1; and

Figure 3 is a sectional detail view showing a modified form of the nozzle or injector device.

15 Referring now to the drawing in detail, this illustrates the improved apparatus as comprising a supporting structure 10 provided with suitable bearings 12 for the journalling of a shaft 14, to which power may be transmitted in any desired manner, as by means of a pulley 15. The standard 10 is formed with a supporting flange 16 to which is secured, as by means of screws 17, the outer edge of a casing 18 which is formed with a central packing structure 20 for the shaft 14, and also with a flange 21 for attachment, as by screws 22, to the pump casing 24, all as illustrated in Figure 1. The casing 24 is constructed to provide an outer chamber 25 and also an interior volute shell or housing 26 forming an impeller chamber 27 enclosing an impeller member 29 of conventional form having the vanes or blades 30, and secured to the end of the shaft 14. 20

25 The chamber 25 is provided with the main suction intake connection 32, and the housing 26 is formed with an extension 33 providing an intake 30 passage 34 from the bottom portion of the chamber 25 and discharging centrally through an opening 35 into the impeller chamber 27. Preferably both of said chambers 25 and 27 are provided with suitable drain outlet plugs 36 and 37, 40 respectively.

35 The housing 26 is formed with a discharge extension 38 fitted with a upwardly projecting and expansible tubular member 40 of rubber or other appropriate flexible or resilient material 45 adapted to expand and contract in the manner and for the purpose hereinafter explained. The member 40 is clamped to the upper end of the extension 38 by means of a suitable clamping band 41. The upper end of the member 40 projects within a Venturi-type tube section 42 secured within an opening 44 provided in the bottom of a housing 45 which provides an upper discharge chamber 46 having a discharge outlet 48 and a 50 filler plug 49 for the supply of priming fluid to 55

the apparatus whenever necessary. The interior of the tube section 42 is somewhat larger than the diameter of the discharge extension 38 carrying the tubular member 40, as clearly shown in Figure 2. The upper end of said member 40 is normally contracted to leave an annular space 50 between it and the lower end portion of the tube 42 for recirculation of the priming liquid, whereas operation of the pump in the priming action causes the member 40 to expand more or less in accordance with the needs of the priming action, either to simply restrict the return flow of liquid through the space 50 as the priming action progresses, or to completely shut off all such return flow or recirculation after the pump has been completely primed, as indicated by the dotted lines in Figure 2.

In the operation of priming, there is of course a supply of liquid in the chamber 25, preferably on a level approximately with the pump intake 32, and the lower end of the intake passage 34 is located adjacent to the bottom to enable the impeller to utilize practically the full capacity of the chamber 25; however the chamber 25 itself could be made sufficiently shallow to make the extension 33 unnecessary. The operation of the impeller in pumping the liquid out of the chamber 25 into upper chamber 46 creates an initial vacuum in the lower chamber 25. The degree of vacuum is further enhanced by the injector effect produced by the discharge through the tube 40, which is initially contracted and thereby provides an annular space 50 between it and the tube section 42 through which air is sucked upward into the upper chamber. The tube 40 being of nozzle shape during this priming operation, this obviously promotes the aforesaid injector action, while the annular space 50 serves also as a return passage for recirculation of the liquid from the upper chamber into the lower chamber for use in priming. The priming action takes place in a somewhat intermittent fashion, i. e., the impeller becomes air-bound intermittently, followed by the pumping of air through the nozzle tube 40, in which operation the air undergoes a compressing action and is discharged with air injector effect and further suction of air from the chamber 25 out through the passage 50.

This phase of the priming action might be described as analogous to that produced by a succession of slugs of the liquid which trap the air between the slugs and carry it on through the impeller until the air is finally released in the discharge chamber 46 and allowed to escape by way of the outlet 48. So long as the proper degree of vacuum or suction is not reached in the intake 32, to support the normal pumping operation (as represented by the pump's capacity), the flexible element 40 will not be sufficiently contracted to close the bypass passage 50, thus permitting enough water to recirculate to the pump for priming purposes. The greater the degree of vacuum or suction which is produced, however, the greater will be the degree of contracting action imparted to said flexible element, whereby the latter automatically responds to the priming action for restricting the return flow or recirculation of liquid through the space 50, so that only enough recirculation takes place to meet the needs of the priming operation. This recirculation of the priming liquid continues until the air pressure is sufficiently reduced in the lower chamber 25 to effect complete priming of the pump, with a full flow of liquid taking place through the in-

take to the impeller chamber. When this happens, a full flow of liquid as represented by the pump's capacity is discharged through the outlet 38, whereby the upper portion of the tube 40 is expanded into engagement with the inside of the tube 42 as represented in Figure 1, and by the dotted lines in Figure 2, thus closing the passage 50 and shutting off any return flow of liquid into the lower chamber.

In Figure 3 is illustrated a modification of the nozzle or injector device, in which a nozzle element 40' of rigid or suitable metallic material (i. e., without the contracting or expanding properties of the element 40) is employed, and is mounted for sliding movement upon the discharge extension 38 of the chamber 27. This sliding movement may take place within limits permitted by the key 53 and keyway 54 provided between said parts 38 and 40'; and, if desired, the length of said keyway may be such as to prevent the entire closing of the byflow space or passage 50 after the pump is fully primed, in which case the injector action will be continued to produce a supplemental flow or discharge of liquid into the discharge chamber 46 for increasing the pumping capacity beyond that of the impeller chamber itself, as will be readily understood. Obviously the action of the sliding nozzle 40' will be in all respects similar to that of the flexible element 40 as regards producing the injector action already described, and also automatically regulating the size of the return flow passage 50 to meet the needs of the priming function from the initial priming stage up to the time when the pump becomes fully primed.

In some cases, as where the pump is to be operated against a relatively low discharge head and hence with small back pressure, it may be advantageous to key said element 40' for operation as a rigid, fixed injector nozzle, leaving a suitable byflow space 50, but omitting the sliding and automatic regulating function, and still securing the benefit of the increased pumping capacity above referred to.

It will therefore be seen that I have devised a practical and efficient as well as simple and inexpensive self-priming construction, and that the same is of such a type as to require none of the valves ordinarily needed in self-priming devices. That is to say, the impeller chamber and space for the priming supply of liquid are below both the intake 32 and the nozzle structure regulating the discharge to the chamber 46, so that an air space is left between said nozzle structure and the intake; or in other words, the intake and outlet sides of the impeller are left with a means of direct communication, for siphon-breaking purposes, independent of the passage through the impeller chamber, thereby preventing the sucking away of the priming liquid which would otherwise take place. Consequently this eliminates the necessity of valves or the provision of any other mechanical or structural features for such purpose, such as the use of large suction traps to prevent the loss of the priming charge. Moreover this feature has the advantage of preventing the efficiency of the pump being materially decreased by the presence of leaks in the connections on the intake side of the pump.

In either type of nozzle or injector element, the flexible type 40, or the rigid type 40', said element performs the double function of a nozzle for carrying out the injector action, and also by expanding and contracting (or sliding movement in

the case of the element 40') a regulating function for restricting or varying the extent of the return flow or recirculation of the liquid back through the bypass 50. As already indicated, 5 such return flow may be entirely shut off when the pump is fully primed, by adapting said adjustable element to entirely close said passage; or if preferred, and particularly in the case of the element 40', some space may be left for further injector action, even after the pump is 10 primed, for producing a further or supplemental flow of liquid in excess of the full normal capacity of the pump as represented by the capacity of the impeller chamber alone.

15 It may also be pointed out that the flexible and expandable properties of the tube 40 results in some relative slipping engagement between it and the mouth of the tube 42, which tends to prevent any sticking tendency, which effect may 20 be somewhat increased by slightly flaring the lower lip of the tube 42 as shown. While I have indicated rubber as a suitable material for the composition of the tube 40, any flexible material having equivalent expanding and collapsing properties 25 may be employed for the purpose, and other modifications or changes in the construction may readily be made within the spirit and scope of the invention.

I therefore desire to be understood as reserving the right to make whatever changes may properly fall within the scope of the appended claim.

What I claim, and desire to secure by Letters Patent, is:

Self-priming pump apparatus comprising, a structure providing an intake chamber and a discharge chamber connected by a communicating passage, pumping means in said intake chamber, and a tubular expandable element forming a part of the discharge conduit from the pumping means to said communicating passage, a part of said element being normally contracted into nozzle form projecting into said communicating passage and expanding automatically under internal pressure of the full discharge flow from the pumping means for cutting off return flow of the priming liquid after the pumping means is completely primed, the mouth of said communicating passage being slightly curved for facilitating disengagement of the expandable element on contraction of the latter to normal condition.
